UNITED STATES PATENT OFFICE.

JOHN FAULDS, OF OAK PARK, ILLINOIS, ASSIGNOR OF ONE-HALF TO JOHN I. MARSHALL, OF CHICAGO, ILLINOIS.

COMBINED PORTABLE OVEN AND PROOF-BOX.

1,238,995.

Specification of Letters Patent.

Patented Sept. 4, 1917.

Application filed April 25, 1917. Serial No. 164,353.

To all whom it may concern:

Be it known that I, JOHN FAULDS, a citizen of the United States, and resident of Oak Park, county of Cook, and State of Illinois, have invented certain new and useful Improvements in Combined Portable Ovens and Proof-Boxes, of which the following is a specification, and which are illustrated in the accompanying drawings, forming a part thereof.

The invention relates to bake ovens and more particularly to those which are adapted for use in situations where the available space is limited and where it is desirable practice to proof a quantity of loaves preparatory to baking while a previously prepared batch is being baked. To this end the invention contemplates a construction which comprises an oven and a proof box of substantially equal capacity and which occupies only the amount of floor space which would be required for the oven alone. The object of the invention is to provide an efficient portable oven which is of inexpensive construction and which is arranged with especial reference to the convenient handling of a given output in a limited space.

In the accompanying drawings,

Figure 1 is a front elevation partly broken away, and showing both the external appearance of the combined oven and proof box, and some of the features of interior construction,

Fig. 2 is a top plan view partly broken away,

Fig. 3 is an upright transverse sectional view,

Fig. 4 is an end view partly broken away to show the oven doors in open position, and

Fig. 5 is a detail perspective view showing the proof box with the oven removed therefrom, the cover of the proof box being partly broken away.

The proof box 10 is preferably constructed to provide a base or stand upon which the oven 11 is removably supported. As shown, the proof box 10 is formed with corner angle posts 12 and side and rear wall plates 13, 14, the corner posts 12 being extended above the plates 13 and 14. Horizontal angles 15 connect the angle posts 12 near their upper ends and form a seat upon which the oven 11 rests. The front wall of the proof

box extends to the corresponding angle 15 and is constructed to provide doors 17, 18 for the introduction and removal of the loaves of bread. If desired a shelf 19 may be provided within the chamber of the proof box 10. In this event the shelf is arranged to provide openings, as 20, about its margin. The circulation of air within the chamber of the proof box for maintaining substantially the same temperature both above and below the shelf is thus permitted. The proof box 10 is preferably also provided with a cover 54. This cover is desirably located at the level of the upper edges of the side and rear wall plates 13, 14. An air space 55 is thus provided between the bottom 21 of the oven and the cover 54 of the proof box with openings 56 extending along the sides and back of the structure. If now the bottom 21 of the oven is formed with openings 57, a circulation of air will be maintained through the air space 55 when the oven is in operation.

The oven 11 may be constructed with permanently connected walls and all of these walls, including the bottom 21 preferably comprise inner and outer plates, as 22, 23, of sheet metal, with an intermediate layer of insulating material. In order that the capacity of the oven may be substantially the same as that of the proof box, the oven is shown as being provided with upper and lower baking shelves or hearths 25 and 26. As it is desirable that these hearths should be without intermediate supports and that provision should be made for the circulation of air and heated products of combustion about their margins, the construction of each hearth may comprise a pair of horizontal angle irons, as 27 and 28, each of which extends from end to end of the oven chamber and is spaced apart from the front or rear wall of the oven to provide an intervening flue space 29. The angle irons 27 and 28 are each supported at their opposite ends by being secured against upright angles 30 or 31 which are in turn secured against the end walls of the oven upon the inside. The angle irons 27 and 28 are so positioned as to provide inturned horizontal flanges 32 at their lower edges and a series of T-irons 33 extend between and connect the horizontal flanges 32, of the front and rear angle irons 27 and 28 at intervals. A frame work is thus provided for supporting the tiles, 110

2
as 34 which form the floor of the hearth, while the location of the upright angle irons 30 and 31 against the end walls of the oven insure the provision of intervening flue spaces 35 at the ends of the hearth.

5 If the oven is to be heated by gas, a horizontal baffle plate 36 is centrally located below the lower hearth, as 26, and a series of gas burners 37 are located below the baffle plate 36. The baffle plate 36 may be of sheet metal and is supported in any convenient manner, as upon legs 58 which extend to the bottom of the oven chamber. All of the burners 37 may be served from a 10 common gas pipe, as 38, which extends horizontally in front of the oven. The heated products of combustion are permitted to circulate through the flue spaces 29 and 35 at the margins of the hearths 25 and 26, and 15 they escape from the oven chamber through a stack, as 39. When this stack is centrally positioned at the top of the oven, as shown, a horizontal baffle plate 59, having openings 60 is preferably located near the top of the oven chamber and extends the full distance 20 between the side and end walls of the oven. 25 The front wall, as 40, of the oven, is shown as being provided with two door frames 41 and 42. The door frame 41 serves to receive a panel 43 through which the burners 37 are extended and this panel is preferably also provided with a damper 44. If desired, brackets, as 45, may be secured against the panel 43 adjacent its opposite ends for supporting the gas pipe 38.

30 The door panel 42 carries two sets of doors, as 46 and 47, one for serving each of the hearths 25 and 26. As the oven will usually be constructed of such small size 35 that a peel will not ordinarily be used, the doors 46 and 47 preferably open inwardly. As shown, each door comprises upper and lower panels 48 and 49. In the closed position of the door, these panels meet upon a 40 horizontal line at the mid height of the corresponding door opening and the panels are mounted to swing upon horizontal pivots 50 and 51 at their upper and lower edges respectively. The two panels 48 and 49 of 45 each door are operatively connected through a pair of intermeshing gear segments 52 and 53, one rigidly connected with each panel. Each door may accordingly be opened or 50 closed by engaging either of its panels, or 55 one of the corresponding gear segments 52, 53. The inward movement of the panels for opening the door insures that the margins of the door opening will be relatively cool to facilitate the introduction and removal 60 of loaves, without the use of a peel. As the upper panel 48 of each door extends horizontally inward from the upper edge of the door opening in its own position, it serves to substantially restrict the escape of 65 heat from the oven chamber when the corre-

sponding door is opened. The arrangement enables a uniform baking temperature to be obtained throughout the entire area of both hearths while the damper 44 and the openings 57 in the bottom of the oven insure the 70 admission of sufficient air to obtain perfect combustion of the gas.

While the chamber of the proof box 10 is warmed by the transmission of heat downwardly from the oven 11, it is important 75 that this transmission of heat should not be too rapid and that it should extend uniformly to the entire chamber of the proof box. For this reason the bottom of the oven chamber is preferably formed with the intermediate insulating layer 24. The transmission of heat to the chamber of the proof box 10 is rendered even more gradual and uniform if the cover 54 of the proof box is 80 made in the form of a shallow pan and this 85 pan is filled with water. As shown, the cover 54 is provided with an upstanding marginal flange 61 but this flange does not extend to the corresponding horizontal angles 15. The openings 56 are those located 90 above the rim of the said pan and air entering these openings is drawn over the surface of the water contained in the pan before entering the chamber of the oven 11 through the openings 57. The use of water 95 in the said pan accordingly serves to improve the baking by supplying moisture to the bake chamber.

I claim as my invention:

1. In combination, a proof box having an 100 imperforate flat cover, an oven having horizontal dimensions substantially equal to those of the proof box superimposed upon the proof box, the bottom of the oven being spaced apart from the cover of the proof box to provide a flue space between said parts having a free inlet opening and the bottom of the oven being formed with an opening connecting said flue space with the oven chamber, a gas burner within the oven 105 chamber, and a flue leading out of the oven chamber.

2. In combination, a proof box, a water pan constituting a cover for the proof box and a bake oven superimposed upon the 110 proof box above the said water pan.

3. In combination, a proof box, a water pan constituting a cover for the proof box, an oven superimposed upon the proof box above the said water pan, the bottom of the 115 oven being spaced apart from the rim of the water pan to provide a flue space between said parts having a free inlet opening and the bottom of the oven being formed with an opening connecting said flue space with the oven chamber, a gas burner within the oven 120 chamber, and a flue leading out of the oven chamber.

4. In combination, a proof box, a water pan constituting a cover for the proof box, 125

- an oven having horizontal dimensions substantially equal to those of the proof box and water pan superimposed upon the proof box above the said water pan, the bottom of 5 the oven being spaced apart from the rim of the water pan to provide a flue space between said parts having a free inlet opening and the bottom of the oven being formed with an opening connecting said flue space 10 with the oven chamber, a gas burner within the oven chamber and a flue leading out of the oven chamber.
5. In combination, a proof box, a water pan constituting a cover for the proof box,
- and a bake oven having horizontal dimensions substantially equal to those of the proof box and water pan superimposed upon the proof box above the said water pan. 15
6. In combination, a proof box, a water pan constituting a cover for the proof box, 20 and a bake oven superimposed upon the proof box above but spaced apart from the said water pan, the bottom of the oven being formed with an opening connecting the space immediately over the water pan with 25 the oven chamber.

JOHN FAULDS.
